The patent or application file contains at least one drawing executed in color. Copies of this patent or patent application publication with color drawing(s) will be provided by the Office upon request and payment of the necessary fee.

FIG. 1 is a front right perspective view of a first embodiment of a medical processor;

FIG. 2 is a top plan view thereof;

FIG. 3 is a bottom plan view thereof;

FIG. 4 is front elevational view thereof;

FIG. 5 is a rear elevational view thereof;

FIG. 6 is a left elevational view thereof;

FIG. 7 is a right elevational view thereof;

FIG. 8 is a front left perspective view thereof;

FIG. 9 is a front right perspective view of a second embodiment of a medical processor;

FIG. 10 is a top plan view thereof;

FIG. 11 is a bottom plan view thereof;

FIG. 12 is front elevational view thereof;

FIG. 13 is a rear elevational view thereof;

FIG. 14 is a left elevational view thereof;

FIG. 15 is a right elevational view thereof;

FIG. 16 is a front left perspective view thereof;

FIG. 17 is a front right perspective view of a third embodiment of a medical processor;

FIG. 18 is a top plan view thereof;

FIG. 19 is a bottom plan view thereof;

FIG. 20 is front elevational view thereof;

(Continued)

FIG. 21 is a rear elevational view thereof;
 FIG. 22 is a left elevational view thereof;
 FIG. 23 is a right elevational view thereof;
 FIG. 24 is a front left perspective view thereof;
 FIG. 25 is a front right perspective view of a fourth embodiment of a medical processor;
 FIG. 26 is a top plan view thereof;
 FIG. 27 is a bottom plan view thereof;
 FIG. 28 is front elevational view thereof;
 FIG. 29 is a rear elevational view thereof;
 FIG. 30 is a left elevational view thereof;
 FIG. 31 is a right elevational view thereof;
 FIG. 32 is a front left perspective view thereof;
 FIG. 33 is a front right perspective view of a fifth embodiment of a medical processor;
 FIG. 34 is a top plan view thereof;
 FIG. 35 is a bottom plan view thereof;
 FIG. 36 is front elevational view thereof;
 FIG. 37 is a rear elevational view thereof;
 FIG. 38 is a left elevational view thereof;
 FIG. 39 is a right elevational view thereof; and,
 FIG. 40 is a front left perspective view thereof.
